CHARLES B. SAWYER, OF CLEVELAND HEIGHTS, OHIO, ASSIGNOR, BY MESNE ASSIGNMENTS, TO THE CLEVELAND TRUST COMPANY, OF CLEVELAND, OHIO, A CORPORATION OF OHIO

PIEZO-ELECTRIC DEVICE

REISSUED

Application filed May 6, 1927, Serial No. 189,443. Renewed November 18, 1930.

This invention relates to piezo-electric material and more particularly to an improved method and means for utilizing the piezo-electric effect of such material.

5 In piezo-electric devices for use at audio frequencies various piezo-electric materials such as quartz and the like have been employed. In general, however, the quartz has not been found sensitive enough for such 10 work so that Rochelle salt crystals have been used for this purpose, due to the greater piezo-electric effect obtained therefrom. The Rochelle salt crystals usually employed for such purposes, however, have had certain disadvantages, such as inconstancy of the piezo-electric effect produced, non-permanency of the crystals, etc.

An object of this invention is to provide piezo-electric elements of rugged character.

20 A further object of the invention is to provide piezo-electric elements of uniform character giving uniform piezo-electric results.

Another object of the invention is to provide piezo-electric elements of relatively 25 great sensitivity or relatively great piezo-electric effect.

30 A further object of my invention is to provide piezo-electric elements whereby the motion of the elements due to an electrostatic field may be magnified to give a correspondingly greater mechanical effect.

Another object of this invention is to provide a piezo-electric element of advantageous piezo-electric characteristics capable of being produced by economical use of piezo-electric material.

40 A further object of the invention is to provide a piezo-electric element suitably constrained whereby when the element is subjected to an electrostatic field the element may be given a bending motion to provide a magnified mechanical motion thereof.

Another object of my invention is to provide an improved method for utilizing the 45 piezo-electric effect of piezo-electric material.

A further object of this invention is to provide piezo-electric devices whereby improved piezo-electric effects may be obtained.

50 Other objects of my invention will be ap-

parent to those skilled in the art from the following description and annexed drawings.

My invention contemplates generally the provision of piezo-electric elements of permanent and sensitive characteristics, said elements embodying piezo-electric material suitably constrained whereby a magnified mechanical motion of said element may be obtained when subjected to an electrostatic field. More specifically, my invention contemplates a piezo-electric element embodying a piezo-electric material arranged to elongate or contract when subjected to a given electrostatic field, the said material being suitably constrained whereby under said given electrostatic field a bending motion may be produced to obtain a magnified mechanical motion of the element.

In the drawings:

Figure 1 is a perspective view of a Rochelle salt crystal from which the piezo-electric material for my invention may be obtained.

Fig. 2 is a perspective view of a slab of piezo-electric material such as Rochelle salt, portions thereof for my improved device being indicated in dotted lines.

Fig. 3 is an end elevation of a piezo-electric element of my invention, said element being mounted on a suitable support.

Fig. 4 is an end elevation showing a modified form of element mounted on a support.

Fig. 5 is a front elevation of the structure shown in Fig. 4.

Fig. 6 is an end elevation of another modified form of element contemplated by my invention mounted on a suitable support.

Fig. 7 is an end elevation of the structure shown in Fig. 6 showing in exaggerated form the motion of the element when subjected to an electrostatic field.

Fig. 8 is a front elevation of a piezo-electric device contemplated by my invention embodying a modified form of element, said device embodying a jewel for cutting phonograph records; and

Fig. 9 is an end elevation of the structure shown in Fig. 8, a conical acoustic diaphragm being shown associated with the element.

While various piezo-electric materials may be employed in constructing an element ac-

rding to my invention, I prefer to employ erefor portions obtained from Rochelle salt ystals. Thus, the material for an element my invention may be obtained from a ochelle salt crystal 1 as illustrated in Fig. 1, e said crystal having the major longitudi- ll axis $c-c$, the major transverse axis $b-b$ nd the minor axis $a-a$. As an illustration one manner in which my improved element ay be constructed, I may cut or otherwise obtain from a crystal 1 or portion thereof a ab 2 illustrated in Fig. 2, said slab being referably cut so that its parallel faces 3 are ibstantially parallel to the major crystalline xes and substantially perpendicular to the minor crystalline axis. It will be under-ood, however, that a slab such as 2 might be btained from other piezo-electric materials.

At 4 and 5 in dotted lines in Fig. 2 I have lustrated how portions to be used in my nproved element may be obtained from the lab 2. At 4 is shown a portion of trapezoidal hape whereas at 5 is shown a portion of sub- stantially rectangular shape. The portions 4 nd 5 are preferably so cut from the slab 2 hat the longitudinal axes M—M and N—N re at substantially 45 degrees to the major rystalline axes, for reasons to be further dis- ussed hereinafter. The faces of the portions 4 and 5 are substantially parallel. It will be understood, of course, that the portions 4 and 5 may be cut directly from a crystal such as 1, or a portion thereof.

In Fig. 3, the crystal portion 6 is shown secured at one end thereof to a suitable sup- port 7 such as of lead by adhesive material 8 such as, for example, shellac or Canada oalsam. The faces 9 and 10 of the portion 6 may be of rectangular or trapezoidal shape as illustrated in Fig. 2 or of any other suitable shape. To the face 10 is shown secured a suitable electrode 11 such as of tin foil, which electrode preferably contacts with a relatively large portion of the face 10. The wire 12 is connected to the electrode 11. To the opposed face 9 is shown secured a portion 13 which may be of metal, such as aluminum, and may be relatively thin but of sufficient strength to constrain the crystal portion 6. The crystal portion 6 and metal portion 13 constitute what may be termed the piezo- electric element 14. The portion 13 prefer- ably, though not necessarily, is co-extensive with the face 9 of the portion 6 and is prefer- ably secured to said portion throughout said face 9 as by suitable adhesive material, the portion 13 being secured to the support 7 as by the adhesive material 8. A wire 15 is secured to said metallic portion whereby the portion 13 may act as an electrode. If the crystal portion 6 is cut from a crystal in the manner indicated in Fig. 2, the said portion 6 when subjected to an electrostatic field by the electrodes 11 and 13 will tend to contract or elongate, depending upon the direction of

said field. Since, however, the motion of said portion 6 is constrained by the portion 13, the crystal portion 6 is not free to elongate or contract, but actually undergoes a bending motion, whereby the upper edge 16 of the crystal portion 6 actually has a greater me- chanical motion than if the crystal portion 6 were unconstrained by the portion 13.

In Figs. 4 and 5 I have shown a modified form of my invention wherein the crystal portions 17 and 18 are shown in juxtaposed position, the said portions being both secured to a support 19 by adhesive material 20. The faces 21, 22, 23 and 24 of the crystal portions 17 and 18 may be of rectangular shape, as shown in Fig. 5, or of any suitable shape such as discussed in connection with Fig. 3. The adjacent faces 22 and 23 may be secured to each other throughout their extent by suit- able cement whereby the crystal portion 17 acts to constrain the motion of the crystal portion 18, and vice versa. Electrodes 25 and 26 are shown as associated with the faces 21 and 24 and wires 27 and 28 and secured re- spectively to said electrodes. The crystal portions 17 and 18 are so oriented that under a given electrostatic field one of said crystal portions tends to contract and the other cry- stal portion tends to elongate longitudinally. Under such conditions, when the piezo-elec- tric element 29 comprising the crystal por- tions 17 and 18, is subjected to an electrostatic field by means of the electrodes 25 and 26, a greater bending motion of the top edges 30 and 31 is obtained, due to the simultaneous 100 contraction of the portion 17 and elongation of the portion 18, and vice versa.

In Figs. 6 and 7 are shown another modi- fied form of piezo-electric element comprising the crystal portions 32 and 33 having the adjacent edges 34 and 35, said portions being secured to the support 36 by suitable adhesive material 37. To the outer faces 38 and 39 are shown secured electrodes 40 and 41 respectively connected by the wires 42 and 43 to a single wire 44, said electrodes 40 and 41 thereby forming a single terminal. Interme- diate the inner faces 34 and 35 is shown a rela- tively thin electrode 45 which preferably is coextensive with the faces 34 and 35. Such electrode may be constituted of aluminum foil. To said electrode is secured a wire 46. The electrode 45 thus forms one terminal and the electrodes 40 and 41 the other terminal. The crystal portions 32 and 33 are preferably so oriented that under a given electrostatic field both portions tend to expand or contract longitudinally. When a given voltage is applied to the wires 46 and 44 it will be readily seen that the crystal portions 32 and 33 are subjected to electrostatic fields in op- posite directions, whereby under said given voltage the portion 32 will tend to contract longitudinally and the portion 33 to expand longitudinally, and vice versa. As a net re-

therewith. In this modification the arms 13' are rigidly attached to the brackets 12 and the pins 27' have revolvably mounted upon them rollers 37' which in this modification 5 serve as the stops to limit the deflection of the member 8'. The ends of the clamps 16' are in the form of pins upon which rollers 18' are revolvably mounted so as to facilitate movement of the member 8' therewith. Similarly the pin 28' carried by the rod 6 has 10 mounted upon it a roller 7' adapted to bear against the member 8' intermediate the two rollers 37' and slightly displaced therefrom. Another advantage of this modification in addition to compensating for slippage of the 15 member 8' past the deflecting means, is that it may in this form be used upon a stressed member 8' which is moving in relation to the measuring device, such as a belt or the like, and thus used as a dynamometer to measure 20 the force being exerted by the stressed member.

A portion of one wall of the chamber 1 is 25 formed by a plate 41 movable in respect thereto by an adjusting screw 42 having its inner end in engagement with the plate 41 and threaded through a bracket 43 rigid with the chamber 1. This movable plate provides 30 convenient means for compensating for variations in pressure of the fluid 31, resulting from variations in temperature, and which would otherwise tend to produce inaccuracies in the reading of the indicating and recording instruments.

35 The operation of my device is substantially as follows:

The indicating gauge 32 should first be 40 observed to determine whether or not the hand points directly to the zero mark when the instrument is not positioned upon the stressed member. If this is not the case the proper adjustment may be obtained by manipulating a screw 42 to increase or decrease the pressure of a fluid 31, as the requirements 45 of the case shall dictate. Then the device is positioned upon the stressed member 8, as previously described, and the screws 22 tightened until the ends 18 of the clamps 16 pull the member 8 into contact with the ends 37 of the arms 13, or the rollers 37', depending upon which modification of the 50 device is being employed. Owing to the displacement of the end 7 of the rod 6 from a line joining the ends 37 of the arms 13 a deflection in the member 8 will thus be produced; and if the member 8 is under tension 55 a side thrust will be produced against a rod 6 to compress the receptacle 3 and its contained fluid, increasing the pressure thereof. 60 This pressure will be communicated to and indicated by the pressure gauge 32 or to a recording instrument in the event that such is the type of instrument being employed, or both. The relation between the indicated or 65 the recorded pressure, as the case may be,

and the tension in the member 8 is given by the calibration curve of the device obtained by calibration in the usual manner.

I claim:

1. A device for measuring the stress imposed upon a member, comprising a chamber, a piston reciprocal within said chamber, a receptacle of flexible material disposed within and conforming to said chamber and piston, a rod carried by said piston and extending from the chamber to engage said stressed member, means for deflecting said stressed member towards said chamber on opposite sides of said rod, a fluid in said receptacle, and means for measuring the pressure of said fluid. 70

2. A device for measuring the stress imposed upon a member, comprising a chamber, a piston reciprocal within said chamber, a receptacle of flexible material disposed within and conforming to said chamber and piston, a rod carried by said piston and extending from the chamber to engage said stressed member, means for deflecting said stressed member towards said chamber on opposite sides of said rod, a fluid in said receptacle, means for measuring the pressure of said fluid, and means for compensating for pressure changes of said fluid. 85

3. A device for measuring the stress imposed upon a member, comprising a chamber, a piston reciprocal within said chamber, a receptacle of flexible material disposed within and conforming to said chamber and piston, a rod carried by said piston and extending from the chamber to engage said stressed member, means for deflecting said stressed member towards said chamber on opposite sides of said rod, a fluid in said receptacle, means for measuring the pressure of said fluid, and means for permitting longitudinal movement of said stressed member in respect to said measuring device while deflected. 90

4. A device for measuring the stress imposed upon a member, comprising a chamber, a compressible receptacle in said chamber, a piston reciprocal within said chamber and adapted to compress said compressible receptacle, a rod carried by said piston and extending from the chamber to engage said stressed member, means for deflecting said stressed member towards said chamber on opposite sides of said rod, a fluid in said receptacle, and means for measuring the pressure of said fluid. 105

5. A device for measuring the stress imposed upon a member, comprising a chamber, a compressible receptacle in said chamber, a piston reciprocal within said chamber and adapted to compress said compressible receptacle, a rod carried by said piston and extending from the chamber to engage said stressed member, means for deflecting said stressed member towards said chamber on opposite 115 sides of said rod, a fluid in said receptacle, and means for measuring the pressure of said fluid. 120

sides of said rod, a fluid in said receptacle, means for measuring the pressure of said fluid, and means for compensating for pressure changes of said fluid.

6. A device for measuring the stress imposed upon a member, comprising a chamber, a compressible receptacle within said chamber, a piston reciprocal within said chamber and adapted to compress said compressible receptacle, a rod carried by said piston and extending from the chamber to engage one side of said stressed member, a pair of brackets extending from said chamber on opposite sides thereof, a clamp pivoted to each of said brackets and adapted to engage the other side of said stressed member, means for tightening said clamps to deflect said member towards said chamber on opposite sides of said rod, a fluid in said receptacle, and means for measuring the pressure of said fluid.

7. A device for measuring the stress imposed upon a member, comprising a chamber, a compressible receptacle within said chamber, a piston reciprocal within said chamber and adapted to compress said compressible receptacle, a rod carried by said piston and extending from the chamber to engage one side of said stressed member, a pair of brackets extending from said chamber on opposite sides thereof, a clamp pivoted to each of said brackets and adapted to engage the other side of said stressed member, means for tightening said clamps to deflect said member towards said chamber on opposite sides of said rod, a fluid in said receptacle, means for measuring the pressure of said fluid, and means for compensating for pressure changes of said fluid.

8. A device for measuring the stress imposed upon a member, comprising a chamber, a compressible receptacle within said chamber, a piston reciprocal within said chamber and adapted to compress said compressible receptacle, a rod carried by said piston and extending from the chamber to engage one side of said stressed member, a pair of brackets extending from said chamber on opposite sides thereof, a clamp pivoted to each of said brackets, a roller revolvably mounted on each of said clamps and engaging the other side of said stressed member, means for tightening said clamps to deflect said member towards said chamber on opposite sides of the rod, a fluid in said receptacle, and means for measuring the pressure of said fluid.

9. A device for measuring the stress imposed upon a member, comprising a chamber, a compressible receptacle within said chamber, a piston reciprocal within said chamber and adapted to compress said compressible receptacle, a rod carried by said piston and extending from the chamber to engage one side of said stressed member, a pair of brackets extending from said chamber on opposite sides thereof, a clamp pivoted to each of said

brackets, a roller revolvably mounted on each of said clamps and engaging the other side of said stressed member, means for tightening said clamps to deflect said member towards said chamber on opposite sides of the 70 rod, a fluid in said receptacle, means for measuring the pressure of said fluid, and means for compensating for pressure changes of said fluid.

10. A device for measuring the stress imposed upon a member, comprising a chamber, a piston reciprocal within said chamber, a compressible receptacle within said chamber and adapted to be compressed by said piston, a rod carried by said piston and extending 75 from the chamber to engage one side of said stressed member, a pair of brackets extending from said chamber on opposite sides thereof, a clamp pivoted to each of said brackets and adapted to engage the other side of said stressed member, means for tightening said clamps to deflect said member toward the chamber on opposite sides of the 80 rod, a link pivoted at one end to each of said clamps and at the other end to said rod, a fluid in said receptacle, and means for measuring the pressure of said fluid.

11. A device for measuring the stress imposed upon a member, comprising a chamber, a piston reciprocal within said chamber, a compressible receptacle within said chamber and adapted to be compressed by said piston, a rod carried by said piston and extending from the chamber to engage one side of said stressed member, a pair of brackets extending from said chamber on opposite sides thereof, a clamp pivoted to each of said brackets and adapted to engage the other side of said stressed member, means for tightening said clamps to deflect said member toward the chamber on opposite sides of the 95 rod, a link pivoted at the end to each of said clamps and at the other end to said rod, a fluid in said receptacle, and means for measuring the pressure of said fluid.

In testimony whereof I have signed my name to this specification.

OTTO BERGER GOLDMAN.
